UNITED STATES PATENT OFFICE.

ELMER E. HASSLER, OF CHAPMAN, KANSAS.

HOME GASOLINE STATION.

Application filed July 17, 1925. Serial No. 44,329.

My invention relates to improvements in home gasoline stations, and it consists in the combinations, constructions, and arrangements herein described and claimed.

5 An object of my invention is to provide a home gasoline station which employs novel means for keeping all of the unused gasoline below the surface of the ground, this means including means for draining the gasoline 10 from the outlet pipe back into the reservoir disposed below the surface of the ground, whereby the gasoline is free from being affected by changes in temperature.

15 A further object of my invention is to provide a home gasoline station of the type described which does away with all mechanical hand pumping, and which makes use of the weight of the car, or the weight 20 of the operator himself for forcing the gasoline line from the reservoir up into the gasoline tank of the car.

25 A further object of my invention is to provide a home gasoline station of the type described which is extremely simple in construction and which is durable and efficient for the purpose intended.

30 Other objects and advantages will appear in the following specification, and the novel features of the invention will be particularly pointed out in the appended claim.

35 My invention is illustrated in the accompanying drawing, forming part of this application, in which

Figure 1 is a side elevation of the device, 40 and

Figure 2 is a sectional view through a modified form of nozzle.

45 Figure 3 is a section along the line 3—3 of Figure 1.

50 In carrying out my invention I provide a reservoir R, a pump cylinder C and a platform P. A pipe 1 connects the reservoir R to the cylinder C. A standpipe 2 communicates with the pipe 1 and has its 45 free end connected to a hose H by means of an elbow 3.

55 The gasoline is fed into the reservoir R through an inlet pipe 4. This inlet pipe is normally covered by means of a cap 5. When the piston 6 is actuated in the cylinder C, it draws the gasoline from the reservoir R past a check valve 7 and into the cylinder C. The movement of the gasoline from the reservoir R to the cylinder C is effected when the platform P is moved manually, by the aid of the handle thereon,

from the full line position into the dotted line position. It will be noted from the drawing that the piston rod 8 is housed in a tubular member 9 so as to permit the ready movement of the rod when actuating the piston 6.

60 After the gasoline has been drawn into the cylinder C, the platform P is moved downwardly by either the operator standing 65 upon the platform or the platform may be constructed so as to permit the car to run thereupon so as to have the weight of the car move the platform downwardly. In the present form of the device, I have shown 70 the cylinder C as being large enough to receive approximately one gallon of gasoline and have shown the reservoir R as being adapted to receive fifty or one hundred gallons of gasoline. If the device is used by 75 a single owner, the cylinder C will be made large enough to receive one gallon of gasoline. If, on the other hand, the device is used as a gasoline station, the cylinder C will be made larger so as to receive a number 80 of gallons of gasoline, and the platform P will also be made larger so as to permit the car to ride up upon the platform, thus using the weight of the car to force the platform downwardly and pump the gasoline 85 line into the car.

90 The downward movement of the platform P forces the gasoline from the cylinder C into the standpipe 2 and the hose H. The mouth 10 of the hose H is placed in the inlet opening of the gasoline tank previous to the moving of the platform P in a downward direction. The gasoline will therefore flow into the gasoline tank of the car. The gasoline in flowing through the hose H passes 95 a pet cock 11 and a second check valve 12.

From the foregoing description of the various parts of the device, the operation thereof may be readily understood. The check valve 12 is used for preventing air 100 from flowing through the hose H and into the cylinder C when the platform P is raised into the dotted line position. In this way the movement of the piston 6 into its uppermost position will suck the gasoline 105 from the reservoir R. The check valve 7 permits the gasoline to flow from the reservoir R to the cylinder C, but prevents the gasoline from returning back into the reservoir. When therefore the platform P is moved downwardly, it will force the gasoline 110 through the pipe 2 and the hose H. The

check valve 12 permits the gasoline to flow out through the mouth 10, but prevents any back-flow of gasoline or air.

One of the principal features of the invention is to provide a device in which all of the gasoline will flow back into the cylinder C. After the desired amount of gasoline has been pumped into the car, the operator opens the pet cock 11 and allows air to enter the hose H. It will be seen that the gasoline in the hose H will flow back into the standpipe 2 and from thence to the cylinder C, as the piston is manually raised. All of the gasoline will now be disposed beneath the surface of the ground and will therefore be unaffected by changes in temperature. The novel construction of the platform P obviates the necessity of gears, etc. The device is extremely simple in construction and is durable and efficient for the purpose intended.

In Figure 2 I show a slightly modified form of nozzle in which the check valve 12 and the manually operated valve 11 are combined so as to provide a device of more simple construction. This form of the device is preferably used when the platform P is made large enough to receive a truck or automobile and be actuated by the truck. The mouth 20 is secured to the end of the hose H and the hose in turn houses a manually controlled spring pressed valve. This valve comprises a valve member 21 that is normally held against a seat 22 by means of a coil spring 23. The spring bears against a perforated plate 24. A crank 25 has its eccentric portion slidably disposed in a slot 26. The slot extends transversely to the longitudinal axis of the valve member 21 so as to permit the handle 27 to swing the crank 25 and open the valve against the tension of the spring 23.

The check valve is normally closed and therefore prevents air from entering through

the mouth 20 and passing down through the hose H. In operation the platform P is raised in the ordinary manner to fill the cylinder C with gasoline. The valve member 21 prevents air from flowing through the hose H down into the cylinder C. When the platform is in raised position, the car is driven upon the platform. The valve 21 remains closed and thus prevents the platform P from moving into the full line position. When the operator places the mouth 20 in the gasoline tank of the car, he turns the handle 27 so as to open the valve and leaves the handle in open position until the desired amount of gasoline has been forced into the gasoline tank. This gasoline is forced into the tank by the weight of the car.

After the desired amount has been forced out, the operator closes the valve 21 by the handle 27 and then after the car has been driven off from the platform, he opens the valve.

I claim:

A device of the type described comprising a reservoir for gasoline disposed beneath the surface of the ground, a cylinder disposed beneath the surface of the ground, a pipe connecting said reservoir with said cylinder, a check valve disposed in said pipe for only permitting the gasoline to flow from the reservoir to the cylinder, a piston mounted in said cylinder, a platform adapted to receive a weight so as to actuate the piston, a pipe for conveying the gasoline from the cylinder to the tank in an automobile, a check valve disposed in said pipe for only permitting the gasoline to flow through said pipe in one direction, and a pet cock for admitting air to said last named pipe so as to permit the gasoline in said last named pipe to flow into said cylinder beneath the surface of the ground when said piston is raised a sufficient distance.

ELMER E. HASSLER.
